United States Patent Office.

HENRY OCORR, OF SHEBOYGAN, WISCONSIN.

Design No. 4,741, dated March 28, 1871.

DESIGN FOR CHAIRS.

The Schedule referred to in these Letters Patent and making part of the same.

To whom it may concern:

Be it known that I, HENRY OCORR, of Sheboygan, in the county of Sheboygan and State of Wisconsin, have invented a new and original Design for Chairs, of which the following is a specification.

The design shown in the accompanying drawing relates to "revolving chairs," so called.

The base of the chair is formed of four radical legs, which are united to the central piece, through which the elevating-screw B passes, and extend thence outwardly, each at about right angles with the two adjoining it.

Each leg is formed in the shape shown, and is provided with a curved and symmetrically-shaped projection, a, which extends down as far as the bottom of the screw, and serves to partially screen the lower end of the same.

In each leg are also cut ornamental recesses c d, after the pattern substantially as shown.

The chair-seat A, which is supported above the base

by the screw B, is covered with cane, and of an oval form.

The back of the chair, also covered with cane, has the irregular outline shown at f g.

The front of the seat is ornamented by a pendent piece, D, which is arranged below the seat, and is formed at its lower edge substantially after the pattern shown in the figure.

What I claim as my invention is—

1. The design for the base of a chair, substantially as described and shown.

2. The design for the front of a chair-seat, substantially as shown.

3. The design for a chair, herein shown and described.

In testimony whereof I have hereunto set my hand in the presence of two subscribing witnesses.

Witnesses:

HENRY OCORR.

M. BAILEY,

C. B. NOTTINGHAM.
